UNITED STATES PATENT OFFICE

WALTER A. DALEY, OF CHICAGO, ILLINOIS, ASSIGNOR TO BELL & GOSSETT COMPANY,
OF CHICAGO, ILLINOIS, A CORPORATION OF ILLINOIS

AUXILIARY WATER HEATER OR HEAT-TRANSFER DEVICE

Application filed April 23, 1927. Serial No. 186,064.

My present invention relates to an auxiliary water heater, or heat transfer device. The invention particularly refers to the provision of heads for such a device which assemble with two pairs or groups of tubes, each tube of said pair or groups of tubes being joined together and communicating at one end so that water admitted into one end of one tube will flow therethrough and into the other tube and back in a stream substantially parallel with the stream in the first tube to a locality adjacent the place at which the water is initially admitted into the first tube. A great saving can be effected in the cost of manufacturing such tubes over tubes particularly designed for a particular heater. The heads, which are the subject matter of my present invention, are such that they may be assembled with a boiler used for other purposes, such as the production of steam for heating, and with two pairs or groups of tubes, such as are above referred to so that water introduced into one portion of such heads will flow successively, that is, one after the other, through both pairs or groups of tubes and will then be discharged, or may be thence withdrawn, from another portion of such head. The principle I have employed in the construction of such heads is the provision therein of three chambers—an entrance chamber which has an entrance port and in addition has communication with one tube of one of said pairs or groups of tubes; a discharge chamber which has a discharge port and in addition has communication with a tube of the other of said pairs or groups of tubes; and a blind chamber which has communication with the tubes of both of said pairs or groups which do not enter either said entrance or discharge chambers.

I attain the foregoing objects and results by means of the structures illustrated in the accompanying drawing, in which—

Fig. 1 is a central vertical section of a head in which all of the tubes of the respective pairs of tubes are disposed in the same plane, the head being shown in attachment with a fragment of boiler plate, the tubes

being shown in elevation in assembled relation with the head and boiler plate.

Fig. 2 is a side elevation of the head and boiler plate shown in Fig. 1.

Fig. 3 is a section on line 3—3 of Fig. 1. 55

Fig. 4 is a rear elevation of a form of head in which the pairs of tubes are set side by side instead of end to end with all the tubes in the same plane, the rear plate of the head being removed for clearness. 60

Fig. 5 is a side elevation, similar to Fig. 2, of the structure shown in Fig. 4.

Fig. 6 is a section on line 6—6 of Fig. 4 showing the relation between a pair of tubes, a head, and a boiler plate. 65

Similar reference characters refer to similar parts throughout the several views.

The heads, as heretofore stated, comprise a base or tube receiving portion, 10, and chambered portion, 11. Both of these portions are extended at either end and bored, as at 12, for the passage of stud bolts, 13, tapped into the boiler plate, 14, by means of which stud bolts and nuts, 15, screwed on the tops thereof the entire structure is secured to the boiler plate. The boiler plate is apertured, as at 16, for the passage of the tubes, 17, 17, and 18, 18, of the respective pairs or groups of tubes. 70 75

Both of the head portions 10 and 11 have 80 aligning extensions, 19, 19, and 20, 20, centrally of their sides for the passage of stud bolts, 21. The bores in the extensions 19, 19, in the base plate, 10, being tapped to receive the stud bolts both ends of which 85 are threaded. Nuts, 22, screw on the tops of the stud bolts 21 and down against the extensions 20, 20, of the chambered portion 11 of the head so as to secure the two portions of the head together. 90

The tube receiving portion 10 of the head is bored, as at 23, either in the arrangement shown in Figs. 1 and 3 or 4 and 6, as the case may be, for the receipt of the tubes 17, 95 17, and 18, 18, in which bores the tubes may be either expanded or brazed in accordance with the respective practices as may be desired.

In both forms of head the chambered por-

tion 11 is provided with an inlet, a discharge, and a blind chamber.

In the form of head shown in Figs. 1 to 3 inclusive, the inlet chamber, 24, is preferably located in the lower end of the member 11 and is provided both on the forward end and side with tapped ports, 24a and 24b, for greater convenience in making attachment therewith, and one of the ports is closed with a plug, 24c, as shown in Fig. 1, and into the other is screwed an inlet pipe 24d, as shown in Fig. 3. The inner end of the inlet chamber 24 registers and communicates with the lowermost tube opening 23 in the tube receiving portion 10.

The discharge chamber, 25, is located in the upper end of the portion 11 and is similar in size and shape to the inlet chamber 24 and is likewise provided with tapped end and side ports, 25a and 25b, for the interchangeable receipt of a plug 25c and discharge pipe 25d. The inner end of the discharge chamber 25 registers and communicates with the top tube opening 23 in the tube receiving portion 10 of the head.

The blind chamber, or chamber without exterior opening, in the form of head shown in Figs. 1 to 3, is designated by the reference character 26 and is located directly between the inlet and discharge chambers 24 and 25 respectively. The inner end of the chamber 26 is sufficiently elongated to register and communicate with the two openings 23 in the tube receiving portion 10 which are nearest the center thereof, but the outer or forward end of the chamber 26, having no opening therein, may be reduced, as clearly shown in Fig. 1, which gives plenty of room for the location of the ports 24a and 24b and 25a and 25b in the inlet and discharge chambers respectively.

In the form of head shown in Figs. 4 to 6 inclusive, in which the tubes are disposed in two planes instead of a single plane, a right angled division wall 27, as clearly shown in Figs. 4 and 6, provides the blind chamber 26 at one side of the base of the chambered portion 11 of the head, while a division wall 28 extending at right angles from the central portion of the division wall 27 divides the remaining portion of the chambered portion 11 of the head into an inlet chamber 24 and a discharge chamber 25. In this form of head the lateral ports 24b and 25b are provided in tubular extensions 29 and 30 from the inlet and discharge chambers respectively. These extensions are rendered desirable by the somewhat cylindric form of this variety of head, and in this variety of head the lateral extension 20 on the side opposite the tubular extensions 29 and 30 is located adjacent the inner instead of the outer end of the chambered portion 11 of the head, as clearly shown in Fig. 6.

Having described by invention, what I claim as new and desire to secure by Letters Patent is:

1. An auxiliary water heater comprising groups of tubes the remote ends of which groups are unconnected, the tubes of each group having communication at their remote ends, and a head with which the proximate ends of said tubes communicate, said head being partitioned to provide an inlet and a discharge chamber each having ports and with which chambers a tube of each group of tubes respectively communicates and an unported chamber having communication with the other tubes of said respective groups of tubes and means for securing said head with the tubes to an apertured boiler plate. 70 75

2. An auxiliary water heater comprising a plurality of groups of tubes the remote ends of which groups are unconnected, the tubes of each group having communication at their remote ends, and a head with which the proximate ends of said tubes communicate, said head being partitioned to provide an inlet and a discharge chamber each having ports and with which chambers a tube of each group of tubes respectively communicates and an unported chamber having communication with tubes of said respective groups of tubes, and means for securing said head with the tubes attached, to an apertured boiler plate. 80 90

3. An auxiliary water heater comprising a plurality of groups of tubes the remote ends of which groups are unconnected, the tubes of each group having communication at their remote ends, and a head with which the proximate ends of said tubes are assembled, said head being partitioned to provide an inlet and a discharge chamber each having ports and with which chambers a tube of each of said groups of tubes respectively communicates and means for effecting communication between the other tubes of said respective groups of tubes, and means for securing said head to an apertured metal casing. 100 105 110

4. An auxiliary water heater comprising a head and means for securing said head to an apertured metal casing, said head comprising a casing having symmetrically arranged tube openings in one side thereof, and inlet and discharge ports in another side thereof, and partitions forming compartments each having a tube opening and an inlet or discharge port therein, and a compartment having only tube openings therein. 115 120 125
